UNITED STATES PATENT OFFICE

2,531,753

TWO-STAGE VAPOR CONDENSER

Alfred H. Totten, Youngstown, Ohio

Application March 7, 1946, Serial No. 652,621

1 Claim. (Cl. 220—85)

1

This invention relates to new and useful improvements and structural refinements in vapor condensers, more specifically, to a device of the character herein described, such as may be positioned in the bottom of a liquid storage tank for the purpose of condensing the vapors which are evaporating therefrom and to reclaim the same into the liquid form.

The principal object of the invention is to provide a condenser which is primarily intended for use in gasoline storage tanks, in order to substantially minimize the conventionally experienced losses resulting from evaporation. However, apart from this primary object, the invention may be effectively employed in association with volatile liquids in general.

A further object of the invention is to provide a condenser which is of simple construction and which may be readily and conveniently installed in the storage tank.

Another object of the invention is to provide a condenser which may be easily and conveniently cleaned, without the necessity of disassembling or removing the same from the tank.

An additional object of the invention is to provide a condenser which cannot easily become damaged.

With the above more important objects in view, and such other objects as may become apparent as this specification proceeds, the invention consists essentially of the arrangement and construction of parts as illustrated in the accompanying drawings, in which:

Figure 1 is a cross sectional view of a storage tank, illustrating the invention in situ therein;

Figure 2 is a cross sectional view, taken in the plane of the line 2—2 in Figure 1;

Figure 3 is a side elevation, partially broken away, and illustrating the condenser per se;

Figure 4 is an end view of the subject shown in Figure 3, and

Figure 5 is a cross sectional view, taken in the plane of the line 5—5 of Figure 3.

Like characters of reference are used to designate like parts in the specification and throughout the several views.

Referring now to the accompanying drawings in detail, the invention consists of a condenser structure designated generally by the reference character 10. This structure is of an elongated formation and consists of a plurality of spaced parallel pipes 11 and a plurality of transversely extending tubes 12.

The pipes 11 are closed at the ends thereof and each of the tubes 12 communicates with

5 with two of the pipes, the pipes and tubes being arranged in a polygonal cross sectional formation, as is best illustrated in the accompanying Figures 3, 4 and 5.

With reference now to the accompanying Figures 1 and 2, the installation of the condensers in the storage tanks will now be described, the same being accomplished either singly or in multiple, depending upon the size of the tank and 10 on the rate of evaporation of the liquid therein.

For purposes of illustration, three of the condenser units 10 are shown in the accompanying drawings, each being supported by means of suitable legs 13 in such manner that the longitudinal 15 axis of the condenser lies in a horizontally offset plane.

The condensers are positioned in the bottom portion of a liquid storage tank 14, the latter being provided at the upper end thereof with a 20 vapor collecting dome 15 and a vapor collecting chest 15', these, in turn, carrying the safety valve 16 and the manhole covers 17.

A pair of vapor inlet conduits 18 extend from the dome 15 to the elevated end of one of the 25 pipes 11 of the condenser unit designated separately by the reference character 19. A further conduit 20 extends between the elevated end of another of the pipes 11 in this unit and the dome 15, this last mentioned conduit being used to carry uncondensed gas from the condenser to the dome.

A further condenser unit 21 is connected in series by the pipes 22 to the relatively low end of the unit 19, and as the vapor passes through 30 the condensers, it is liquified and flows through the conduit 23. The latter is connected at one end to the relatively low end of the unit 21, while the remaining end of the conduit 23 communicates with a suitable receptacle or tank 24. It will be noted that the latter is positioned at a 35 relatively lower level with respect to the tank 14 and may, if desired, be suitably placed in an underground location.

The liquid which accumulates in the receptacle 24 may be reclaimed in any convenient manner through a suitable manhole 25 and any vapor which has not liquified during its passage through the condensers 19 and 21 and also, any vapor such as may pass off the liquid in the receptacle 24, is delivered to the dome 15' by a further conduit 26, provided with the shut-off valve 27.

A further condenser unit 28 may also be positioned in the tank 14, the same being provided with a vapor inlet conduit 29. This conduit is 50 similar to the aforementioned conduit 18 and

communicates with the dome 15'. The unit 28 is also equipped with an uncondensed gas conduit 30, this again corresponding to aforementioned conduit 20.

The liquid outlet conduit 31 of the unit 28 however, opens into a further receptacle or tank 32, this being independent of the receptacle 24 and being provided with a ventilating conduit 33. The last mentioned conduit is equipped with a suitable shut-off valve 34 and communicates with the atmosphere. In this manner, the complete storage tank system is not entirely sealed from atmospheric pressure and it will be observed that a relatively small amount of evaporation may still take place through the conduit 33.

If desired, a suitable pipe 35, provided with the shut-off valve 36 may enter through the wall of the tank 14 for connection to either or both of the conduits 20 and 30, and by connecting the outer extremity of the pipe 35 to a source of steam, or the like, the entire condenser system may be effectively "blown-out," for purposes of cleaning or the undertaking of repairs.

It should be understood that while for purposes of convenient reference, the condenser units 19, 21 and 28 are designated by separate reference characters, their construction and operation is similar in nature, as exemplified by the condenser structure designated generally by the reference character 10.

In view of the foregoing, it is believed that the operation of the invention will be clearly understood with reference to the accompanying drawings, and further description thereof at this point is therefore considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

The combination of a volatile liquid storage

tank provided at the top thereof with a vapor collecting dome, a primary condenser unit mounted in an inclined position on the bottom of said tank, a primary condensation receptacle disposed exteriorly of the tank substantially below the bottom of the latter, a primary vapor conduit extending from said dome to the upper end of said primary condenser unit, a primary condensation conduit extending from the lower end of the primary condenser unit to said primary receptacle, a vapor collecting chest provided on the outer surface of said tank, a vapor transmitting conduit extending from said primary receptacle to said chest, a secondary condenser unit mounted in an inclined position on the bottom of said tank, a secondary vapor conduit extending from said chest to the upper end of said secondary condenser unit, a secondary condensation receptacle disposed exteriorly of the tank substantially below the bottom of the latter, and a secondary condensation conduit extending from the lower end of the secondary condenser unit to said secondary receptacle.

ALFRED H. TOTTEN.
